FUSE HOLDER

Herman J. Hammerly, Plainville, Conn., assignor
to The Trumbull Electric Manufacturing Com-
pany, Plainville, Conn., a corporation of Con-
necticut

Application September 14, 1940, Serial No. 356,789

9 Claims. (Cl. 200—134)

This invention relates to what are commonly called clips or holders for fuses or protective relays.

The main object is to provide holders for securely clamping the ends of cylindrical or cartridge type fuses so that they cannot work loose.

A special object is to provide a rugged type of structure the body of which can be stamped from strip or sheet metal such as brass, copper or bronze.

Another object is to provide a device capable of exerting great pressure on a fuse end.

The U-shaped body of the holder is principally formed from strip or sheet stock cut off and bent to shape to receive the end of a fuse and reinforced by one or more transverse bar members which connect the opposite side arms of the holder and support the end of the fuse. The fuse may be clamped in the holder in a number of ways by means of an adjustable member.

Fig. 1 is a perspective view of a fuse with blade tips and holders involving one form of my invention.

Fig. 2 is an exploded perspective showing parts of the holder of Fig. 1.

Fig. 3 is a transverse sectional view of the cam of the fuse holders.

Fig. 4 is an end view of a holder for a fuse with a cylindrical end and showing a different form of clamping device.

Fig. 5 is a longitudinal sectional view of the holder of Fig. 4 with the end of a fuse in place.

Fig. 6 is a perspective view showing another form of clamping device.

The holder is formed of strip or sheet stock chopped off to proper length and width with the grain of the metal extending across the base 10 and up the side arms 11 and 12 so that the bends are across the grain. These sides are shaped to support the end 13 of the fuse and the wedge 14 of the clamping device.

The side arms 11 and 12 are connected by one or more wires or bars 15 which are preferably riveted over so as to tie the arms together and reinforce the holder. These ties also serve to support the end 13 of the fuse, above the bottom of base 10 so that a screw or bolt connection can be made underneath the fuse, and so that added air circulation is obtained.

The wedge 14 is formed of sheet metal rolled into a tubular form and provided with a hole 16 in the top and a slot 17 in the bottom to receive the clamp screw 18 which screws into the base of the holder. The screw threaded engagement of the screw 18 in the base, or the engagement

between the screw and the wedge 14, or both, is made loose enough to permit proper clamping motion of the wedge toward the surface of an inserted fuse end upon tightening of the screw. In this action, the wedge bears on surface 19 of the arm 12. In order to facilitate retraction of the wedge I provide a tongue 20 in the slot 17 of the wedge which extends into the groove 21 in the screw 18.

10 The form shown in Figs. 4 and 5 is designed to accommodate a cylindrical or ferrule end 23 of a fuse. In this case a tapered headed screw 24 is mounted in the lug 25 which extends from the arm 26 of the holder. The other arm 27 engages the fuse end at a point less than 180° away from the point of engagement of the screw head so that the screw when tightened draws the fuse end down against the cross bar 28. The flanged piece 29 serves to limit the endwise movement of the fuse.

15 The form shown in Fig. 6 has a cam headed member 30 eccentrically mounted in the lug 31 on the pivot 32 so that as it is turned it is forced nearer to or further from the fuse end (not shown). A stop 33 permits rotation of the cam head slightly beyond the position in which the eccentric surface most closely approaches the clamping wall on the base, thus locking the cam in clamped position when a fuse is inserted and 20 the cam is turned against the stop. The support is sufficiently resilient to permit the head 30 to lock into place so that it will not work loose accidentally.

25 In this form the arm 34 not only serves as an abutment for one side of the fuse end but it also has a binding clamp 35 which facilitates attachment of a conductor.

It will be seen that each form of construction is simple but inexpensive and yet affords a 30 rugged and effective holder.

I claim:

1. A sheet metal fuse holder with a U-shaped body portion for receiving the end of a fuse, a transverse bar extending between the arms of said U-shaped body portion for reinforcing the side arms of the body portion and for supporting and seating the fuse end and a wedge member adjustable on the body portion and adapted to clamp the fuse end against the body portion.

2. A sheet metal fuse holder with a U-shaped body portion for receiving the end of a fuse, a cross bar connecting the arms of said U-shaped body portion for reinforcing the body portion and for supporting the end of the fuse and a 50 clamping member adapted to be moved into the

space between the arms of the body portion so that a portion thereof engages and clamps the end of the fuse against the body portion.

3. A fuse holder including a U-shaped sheet metal body portion for receiving the end of a fuse, spaced rod members connecting the arms of said body portion for reinforcing said body portion and supporting the end of the fuse, a split tubular sheet metal clamping member movable between the arms of said body portion and screw means for moving said clamping member against the end of the fuse whereby said fuse end is clamped against one arm of the body portion.

4. A fuse holder of sheet metal of U-shape having a lug at one side with a wedge member pivoted thereto and having an eccentric cam-like wall adapted to be clamped against the side of the end of a fuse by rotating the wedge member.

5. A fuse holder of sheet metal of U-shape having a lug at one side with a wedge member pivoted thereto and having an eccentric cam-like wall adapted to be clamped against the side of the end of a fuse by rotating the wedge member and a stop for limiting the rotation of the wedge member.

6. A fuse holder of sheet metal of U-shape having a lug at one side with a wedge member pivoted thereto and having an eccentric cam-like wall adapted to be clamped against the side of the end of a fuse by rotating the wedge member and two spaced tie wires connecting the opposite side arms of the holder for supporting the fuse and reinforcing the arms.

7. A fuse holder of sheet metal having a U-

shaped body portion, a lateral lug on one end of the body portion having an opening, a wedge-shaped member, and a pin eccentrically mounted on the smaller end of said member and rotatable in said opening, said member being formed with a slot in its larger end for receiving a tool to rotate said member.

8. A fuse holder of sheet metal having a U-shaped body portion, a laterally extending lug on the end of each arm of said body portion, a wedge-shaped member pivoted on one of said lugs and having an eccentric cam-like wall adapted to be clamped against the side of the end of a fuse by rotating said wedge member, and a member movably mounted on the other arm of the body portion for clamping a conductor wire.

9. A clamp for the end of an electrical cartridge fuse including a base of sheet metal bent into substantially U-shape, the legs of the U extending vertically and being spaced apart sufficiently to receive the end of a fuse, a rivet extending between the legs and secured to each leg above but near the bight of the U for reinforcing the base and for supporting the end of a fuse in spaced relation from the bottom of the bight, a fuse contacting face on the inside of one of the legs, clamping means for forcing an inserted fuse end toward said rivet and toward said contacting face, said means having a tool-engaging portion manipulable from a vertical position adjacent the ends of the legs of the base, and a bearing for said clamping means on the leg opposite the fuse contacting face.
